US00D618707S

(12) **United States Design Patent**
Schuetz et al.

(10) **Patent No.:** **US D618,707 S**
(45) **Date of Patent:** **** Jun. 29, 2010**

(54) **EXTENDED RUN WATER PUMP**

(75) Inventors: **John David Schuetz**, Owatonna, MN (US); **Matthew Robert Pilcher**, Owatonna, MN (US)

(73) Assignee: **Northern Tool & Equipment Company, Inc.**, Burnsville, MN (US)

(**) Term: **14 Years**

(21) Appl. No.: **29/341,382**

(22) Filed: **Aug. 4, 2009**

(51) **LOC (9) Cl.** **15-02**

(52) **U.S. Cl.** **D15/7**

(58) **Field of Classification Search** D15/7-9; D23/231, 232, 225; 417/410.1, 359, 415-416, 417/234, 321, 265, 405

See application file for complete search history.

CLAIM

The ornamental design for an extended run water pump, as shown and described.

DESCRIPTION

FIG. 1 is a perspective view of an extended run water pump showing our new design;

FIG. 2 is a front plan view thereof;

FIG. 3 is a rear plan view thereof;

FIG. 4 is a right side elevational view thereof;

FIG. 5 is a left side elevational view thereof;

FIG. 6 is a top plan view thereof; and,

FIG. 7 is a bottom plan view thereof.
